UNITED STATES PATENT OFFICE.

FRANK F. YAPP AND ELMER E. ELLIS, OF WATERLOO, IOWA.

WEIGHT-MOTOR.

No. 828,992.

Specification of Letters Patent.

Patented Aug. 21, 1906.

Application filed April 28, 1905. Serial No. 257,798.

To all whom it may concern:

Be it known that we, FRANK F. YAPP and ELMER E. ELLIS, citizens of the United States of America, and residents of Waterloo, 5 Blackhawk county, Iowa, have invented certain new and useful Improvements in Weight-Motors, of which the following is a specification.

Our invention relates to improvements in weight-motors; and the objects of our improvements are, first, to provide appropriate means for regularly and smoothly winding the cable in a uniform layer on the drum, and, second, to combine with the other mechanism means for sounding an alarm shortly previous to the paying out of the last coils of the cable. We have accomplished these objects by the means which are hereinafter shown and described and which are illustrated by 20 the accompanying drawings, in which—

Figure 1 is a side elevation of our improved weight-motor; and Fig. 2 is a transverse sectional view of the same, taken on the line *xx* in Fig. 1.
25 The winding-drum *a* has a crank *c*, and its shaft *d* is supported by the bracket *e*. The cable *b* leads from the winding-drum *a* over an overhead pulley *f*, the latter having an interior thread provided in order to permit it 30 to move longitudinally on the screw *g*. From the pulley *f* said cable passes into the pulley-blocks *l* and *m*, the former being suspended from a cross-bar *k* and the latter being connected to a weight *n*. The screw *g* is fixed in 35 blocks *h*, fastened to the floor-joists.

At *s* we have shown the projecting contact-stud of an alarm-bell, the bell itself not being shown. A flat flexible or elastic spring-plate *r* is at one end attached to a fixed support, so 40 as to permit of its free end overhanging the stud *s*.

The operation of our improved device is as follows: By means of the crank *c* the cable *b* is wound evenly and uniformly over the winding-drum *a*, lifting the weight *n*. We effect 45 the winding of the cable in a regular layer by means of the pulley *f*, which rotates as the cable passes over it. The pulley moves longitudinally along said screw as much distance in 50 the same time as the width of the space uncovered on the winding-drum by the simultaneous paying out of the cable as the weight *n* descends. The effect is the same in winding up, as then the pulley *f* moves in a reverse direction along the screw *g*. The result 55

is to keep the portion of the cable *b* which is between the pulley *f* and the winding-drum *a* in a vertical direction, always perpendicular to the axis of the winding-drum. Consequently the winding will proceed, leaving the 60 coils in contact side by side in a regular even layer without liability to overlap, which might cause a shearing of the cable at the point of overlapping. This improvement also does away with the necessity when winding up the weight of regulating the coiling of the cable by hand, as the action becomes automatic. Another improvement resides in the addition to the mechanism of an alarm, as shown at *r s*. As the weight descends toward its lowermost position the cable *b* uncoils until the pulley *f* approaches closely to its limit of movement in one direction along the screw *g*. When the pulley *f* contacts with the spring-plate *r*, the latter gradually presses 70 in the movable stud *s*, effecting a contact with a bell-alarm, the latter of which may be spring or otherwise actuated or operated by a battery. The bell or other alarm device may be located in any convenient part of the 75 building, such as the kitchen, so as to give warning by its continued ringing of the nearly unwound condition of the winding-drum *a*.

Having described our invention, what we 80 claim as new, and desire to secure by Letters Patent, is—

1. A weight-motor, comprising a winding-drum, a shaft supported parallel to said winding-drum, a pulley lengthwise movable along 90 said shaft, a weight, and a cable extending from said winding-drum over said pulley to said weight.

2. A weight-motor, comprising a winding-drum, a screw fixed parallel therewith, a pulley, interiorly threaded, adapted to move along said screw, a weight, and a cable extending from said winding-drum over said pulley to said weight. 95

3. A weight-motor, comprising a winding-drum, a shaft supported parallel to said winding-drum, a pulley lengthwise movable along said shaft, a weight, a cable extending from said winding-drum over said pulley to said weight, and a device arranged to produce a warning-signal by contact with said pulley when the cable on said winding-drum is nearly unwound. 100

4. A weight-motor, comprising a winding-drum, a screw fixed parallel therewith, a pul- 105

ley, interiorly threaded, adapted to move along said screw, a weight, a cable extending from said winding-drum over said pulley to said weight, and a device arranged to produce 5 a warning-signal by contact with said pulley when the cable on said winding-drum is nearly unwound.

Signed at Waterloo, Iowa, this 14th day of April, 1905.

FRANK F. YAPP.
ELMER E. ELLIS.
